COMBINED BOLSTER CENTER FILLER AND REAR DRAFT LUG UNIT

Emil H. Blattner and Glenn F. Couch, Buffalo, N. Y., assignors to The Symington-Gould Corporation, Depew, N. Y., a corporation of Maryland.

Application July 7, 1950, Serial No. 172,572

14 Claims. (Cl. 213—57)

1

This invention pertains to a combined bolster center filler and rear draft lug unit particularly for use in a railway car or vehicle.

An object of the invention is the provision of an improved skeletonized casting or unit capable of functioning as a combined bolster center filler and rear draft lug component of a railway car.

Another object of the invention is the provision of cross-ribbing or bracing in a unit of the above identified class so that loads imposed along one side thereof will be partially resisted by the other side thereof.

A further object of the invention is to provide diagonally disposed bracing in a unit of the class herein described so that any loads imparted to one side thereof will be resisted by both sides.

The above and numerous other objects will become apparent from the succeeding description taken into consideration with the accompanying drawings which illustrate an exemplification of the invention and wherein:

Figure 1 is a plan view of a unit of the present invention.

Figure 2 is a vertical longitudinal sectional view taken along the lines 2—2 of Figure 1 looking in the direction of the arrows.

Figure 3 is a vertical view partially in section and partially in elevation and taken along the lines 3—3 of Figure 1 looking in the direction of the arrows.

Figure 4 is a vertical view partially in elevation and partially in section and taken along the lines 4—4 of Figure 1 looking in the direction of the arrows.

Referring now in detail to the drawings, wherein like reference characters indicate like parts, the numeral 1 is employed to designate, in a somewhat general manner, a unit capable of functioning as a combined bolster center filler and rear draft lug component of a railway car or vehicle. While the unit is illustrated in the drawings as a casting or of cast metal this embodiment is preferred; however as will be clearly understood by those skilled in the art to which this invention appertains, the unit may be built up as a weldment from various prefabricated sections welded together. As a matter of fact the configuration and relationship of parts lend themselves equally well to the formation of the unit either as a cast or built-up welded component.

The unit, for the sake of clarity and convenience, is hereinafter considered as having a front or forward end or extremity 2 and a rear or back end or extremity 3 and also because the unit

2

occupies such a disposition in a car body (not shown) the unit is positioned in a car body center sill structure 4 (shown only diagrammatically) which desirably is comprised of transversely spaced, vertically directed flanges 5 extending longitudinally of the car body of which it forms a part. The remaining structure of the center sill may be as desired and for the purpose of illustration it may have a top web 6 joining upper extremities of the flanges and outwardly directed horizontal lower legs 7 forming lower terminal members of the sill.

The unit is provided with side walls 8 extending vertically for only a portion of the free height of the sill flanges. The sidewalls are in surface bearing relation with the sill flanges inwardly of the sill. Since these side walls are primarily subjected to buffing or compressive forces directed longitudinally of the car they are therefore spaced transversely of the unit and extend longitudinally of the car for only a portion of the length of the unit for the purpose of lightening the unit and for other reasons hereinafter made apparent.

A bed or base plate or bottom wall 9 extends transversely of the unit to join the side walls adjacent lower or bottom extremities thereof. This bottom wall directed substantially horizontally is bifurcated as at 10 to permit the entrance or free movement of a related extremity of a draw bar (not shown) and transversely spaced, elongated openings 11 are formed in the bed plate in rearward spaced relation with the bifurcation to lighten the unit. Upstanding from the base, as an integral part thereof and adjacent the forward end of the unit at each side thereof, is a vertical or buffing receiving wall or draft lug 12 which stands from a companion or related side wall transversely of the unit. The draft lugs, considered as a pair, only project from the side walls for a predetermined distance as illustrated and this distance is to be governed by the clearance demanded by the draw bar extremity above mentioned. As will be recognized by those skilled in the art, these draft lugs function as bearing walls for a rear follower (not shown) or a draft gear (not shown) of a draft rigging (not shown) so that any buffing forces transmitted to the unit will be received directly by the draft lugs and through the unit be conveyed to the center sill.

The buffing forces above mentioned are not, at all times, equally distributed between the pair of draft lugs; that is to say, during certain executions of the draft rigging above mentioned one

draft lug of a pair may be subjected to a greater buffing load than its companion draft lug and this unequal load is then, ordinarily, transmitted in unequal magnitude to the respective sill flanges 5. This invention is such that irrespective of the unequal or unbalanced loads which may be imparted to the respective forward walls, both flanges of the center sill will receive the loads in equal force. Toward the accomplishment of this function, each vertical inner extremity of a forward wall or draft lug is integrally joined with a related extremity of a rib or intermediate, load transmitting wall 13. Each rib is directed preferably vertically for at least the full height of the side walls and is spaced inwardly of the unit from a companion, related or adjacent side wall. As clearly illustrated, particularly in Figure 1 of the drawings, the ribbing follows, for a given direction, the periphery of the bottom wall bifurcation and as such may be considered as starting from the inner extremities of the draft lugs as integral parts thereof and then being directed diagonally or transversely of the unit at an oblique or acute angle to the side walls. The ribbing forms an X design when considered in plan and therefore the ribs merge into one another when they cross as at 14 on what might be considered as the longitudinal center line of the unit as designated by the diagrammatic line marked A—A on Figure 1 only of the drawings. This crossing of the ribs is preferably at the transverse center of the unit so that each rib is a substantial counterpart of the other rib. Continuing from a crossing of the ribs, each rib is directed in a substantially straight, however diagonal, line toward an extended vertical longitudinal plane of an opposed side wall, or stated in another manner, each rib extends from near one side wall to a plane of the other side wall where it terminates in an auxiliary side wall 15. Each auxiliary side wall is in longitudinal alignment with a side wall and as such is arranged to be in full surface bearing relation with the sill side flange inwardly of the center sill. It will be noted, therefore, that any load imposed on a particular draft lug will be transmitted to one sill side flange by a companion unit side wall and also to the other sill side flange by a companion rib.

In order to tie the ribbing together adjacent lower extremities thereof and particularly that portion thereof which grows out of the crossing toward the rear extremity of the unit, the bottom wall or base plate is extended rearwardly and horizontally as at 16 for this purpose. Because it is believed not absolutely essential to continue the bottom wall entirely transversely of the unit to the extreme rear end 3 thereof, the base plate at this location is cut away or omitted as at 17 thus causing the formation of gussets 18 to strengthen or reinforce the auxiliary side walls and this omission also functions in lightening the unit which is a desirable feature in units of the present type.

So as to properly reinforce the ribbing against shocks to which it will be subjected in service, a diagonally arranged brace or stiffening wall 19 is spaced a predetermined distance in back of each draft lug. Each brace desirably upstands vertically from the bed plate as an integral part thereof but for only a distance approximating one-half the height of the side wall and rib in that area. As previously stated the brace extends diagonally of the unit and is interposed between and forms a part of a related rib and 75

side wall so as to be capable of conveying lateral component forces between a rib and its related side wall. For the same purpose as that above set forth, each rib in the rear of the crossing is 5 also provided with a tie bar or plate 20 which extends from its juncture with the rib in a direction outwardly, diagonally or forwardly of the unit to merge with a rear extremity of an opposed side wall as at 21. A portion of each tie bar and a portion of each related rib are extended 10 vertically or upwardly beyond the upper limits of the ribs and side walls to form an angle shaped crown or comb 22 which terminates preferably short of the center sill top web where it is joined 15 to the top web by means of welds 23; see particularly Figures 2, 3 and 4. These crowns or combs not only assist in a proper positioning of the unit vertically within the center sill but also 20 function as a bond or connecting medium between the unit and center sill about the latter of which more will be contained hereinafter.

As will be understood this unit is disposed in a car body at a location of the body bolster and the car body is connected to a suitable truck 25 (not shown) at this same location through the medium of a king pin (not shown). For the accommodation of the king pin, the unit is provided with a post or cylindrical sleeve 24 which stands upright from the bed plate as an integral part 30 thereof. The post is located on the longitudinal center line of the unit or in longitudinal alignment with the rib crossing to be centrally located transversely of the unit. Because the post is subjected to service horizontal loads this post 35 is reinforced, longitudinally, by aligned triangular knee braces 25 which merge with the base plate. For the same reason the post is joined to the ribbing by vertical, transversely directed tie walls 26. From an inspection of Figures 2 40 and 4 it will be noted that the post has a height equal to only a part of the height of the side walls and ribbing and for this reason, as well as presenting an adequate tie, the portion of each tie wall merging with the post is for a height 45 equal to that of the post and the portion of the tie wall merging with a related rib is for a height equal to the main part of the rib. In order to further reinforce this area of the unit the bottom plate is extended as at 27 outwardly or laterally of the unit beyond the ribs but preferably terminated short of a meeting with the sill side flanges. These portions 27 of the bottom wall are further joined to the ribbing by vertical backup walls 28 which desirably are in transverse alignment with the tie walls and therefore, the post 55 is not only suitably reinforced but the entire area of the unit at this location presents a rugged, skeletonized component.

Various means may be employed to anchor the 60 unit to the center sill and while the conventional means such as rivets (not shown) may be employed it is preferred to follow the teachings outlined in the copending application of Emil H. Blattner, Serial No. 93,800, filed May 17, 1949. This type of fastening may, for convenience, be 65 classified as a plug weld but actually it goes far beyond what this simple classification implies. Both the side wall and the auxiliary side walls of the unit are additionally or inwardly thickened in local, vertically directed, longitudinally spaced areas by pads 29. Vertically arranged in each 70 area are a plurality of drillings 30 which extend only partially into the pads and preferably do not project entirely therethrough. The center sill side flange is provided with a plurality of holes

31 which may be of the same size or slightly larger in diameter than the drillings and with which the holes are in axial alignment. The holes and drillings are filled completely with welds 32 and thus the unit is not only firmly attached to the center sill but in addition all of the holding means are subjected only to shear forces thereby incorporating an ideal condition in the relationship. To further bind the unit to the center sill, an outer vertical edge of each 10 draft lug is so formed to present a triangular pocket with the adjacent sill side flange and this pocket functions as a depository for a weld 33.

From the above it will be noted that various changes and alterations may be made to the illustrated and described construction without departing from the spirit of the invention and scope of the appended claims.

We claim:

1. In a combined bolster center filler and draft lug unit, the combination of, vertical side walls extending partially the length of said unit from one extremity thereof, a bottom substantially horizontal plate joining said side walls at a lower edge thereof, vertical draft lugs extending transversely and inwardly of said unit from said one extremity, and vertical ribbing extending from said bottom plate; said ribbing starting at said draft lugs in transverse spaced relation to said side walls and being directed diagonally of said casting to terminate in auxiliary side walls forming interrupted continuations of said side walls.

2. In a combined bolster center filler and draft lug unit, the combination of, vertical side walls spaced transversely of said unit, a bottom horizontal wall joining said side walls, vertical draft lugs extending transversely of said unit from said side walls, and vertical ribbing extending from said bottom plate; said ribbing joined to said draft lugs in transverse spaced relation with said side walls and extending therefrom diagonally and longitudinally of said unit beyond said side walls to terminate in auxiliary side walls longitudinally aligned with said side walls.

3. In a combined bolster center filler and draft lug unit, the combination of, vertical and longitudinal side walls spaced transversely of said unit, a bottom wall connecting said side walls, vertical draft lugs instanding from and formed integral with said side walls, and vertical ribbing upstanding from said bottom wall inwardly of said unit from said side walls; said ribbing arranged in cross formation and extending from said draft lugs diagonally beyond said side walls to terminate in auxiliary side walls in alignment with said side walls.

4. In a combined bolster center filler and draft lug unit, the combination of, vertical and longitudinal side walls, a bottom wall joining said side walls adjacent a lower extremity thereof, transversely spaced draft lugs extending inwardly of said unit from said side walls adjacent common ends thereof, and vertical ribbing upstanding from said bottom wall in transverse spaced relation to said side walls; said ribbing forming an X and extending from said draft lugs diagonally of said unit to terminate in auxiliary walls parallel with said side walls.

5. In a combined bolster center filler and draft lug unit, the combination of, vertical and longitudinal side walls, a bottom wall joining said side walls adjacent lower extremities thereof, vertical forward walls transversely spaced and extending from said side walls adjacent common extremities thereof, and vertically directed ribbing up-

standing from said bottom wall, said ribbing extending from said forward walls diagonally of said unit beyond said side walls to continue therebeyond in alignment with said side walls.

6. In a combined bolster center filler and draft lug unit, the combination of, vertically and longitudinally directed side walls, a bed wall extending transversely of said unit between said side walls, vertical buffering walls instanding of said unit from said side walls adjacent common extremities thereof, a cylindrical post upstanding from said bed wall, and vertical ribbing upstanding from said bed wall; said ribbing extending from said buffering walls in spaced relation to said side walls and directed diagonally beyond said side walls to terminate in spaced relation to and in alignment with said side walls; said post being positioned between said ribbing.

7. In a combined bolster center filler and draft lug unit, the combination of, vertically and longitudinally directed side walls, a bed wall extending transversely of said unit between said side walls, vertical buffering walls directed inwardly of said unit in transverse spaced relation and from common extremities of said side walls, and a cross ribbing upstanding from said bed wall; said cross ribbing comprising a rib joined to each buffering wall and directed diagonally of said unit beyond an opposed side wall and terminating in an auxiliary side wall in alignment with said opposed side wall.

8. In a combined bolster center filler and draft lug unit, the combination of, vertically and longitudinally directed side walls, a base plate joining said side walls, a forward wall extending partially transversely of said unit from an extremity of a companion side wall and joined to said base plate, and a rib spaced from a companion side wall and connected to said base plate and a forward wall; said rib extending longitudinally and diagonally of said unit to terminate in spaced longitudinal alignment with an opposed side wall.

9. In a combined bolster center filler and draft lug unit, the combination of, vertically and longitudinally directed side walls, a base plate joining said side walls adjacent lower extremities thereof, a forward vertical wall extending partially transversely of said unit from a companion side wall, a rib spaced from a companion side wall and connected to a related forward wall and said base plate; said rib extending longitudinally and diagonally of said unit to terminate in spaced longitudinal alignment with an opposed side wall, and reinforcing walls joining each rib and said base plate.

10. In a combined bolster center filler and draft lug unit, the combination of, vertically and longitudinally directed side walls, a base plate joining said side walls adjacent lower extremities thereof, a forward vertical wall extending partially transversely of said unit from a companion side wall, a rib spaced from a companion side wall and connected to a related forward wall and said base plate; said rib extending longitudinally and diagonally of said unit to terminate in spaced longitudinal alignment with an opposed side wall, a pin post upstanding from said base plate and spaced from said rib, and flanges joining said post and base plate.

11. In a combined bolster center filler and draft lug unit, the combination of, vertically and longitudinally directed side walls, a base plate joining said side walls, a forward wall extending partially transversely of said unit from an extremity of a companion side wall and joined to

said base plate, a rib spaced from said companion side wall and connected to said base plate and forward wall, said rib extending diagonally of said unit and terminating in longitudinal alignment with an opposed side wall, and a king post upstanding from said base plate and spaced from said side walls and rib.

12. In a combined bolster center filler and draft lug unit, the combination of, longitudinally directed vertical side walls, a base plate joining said side walls, a forward wall extending partially transversely of said unit from a companion side wall, a king post upstanding from said base plate intermediate said side walls, and a rib connected to said base plate and forward wall, said rib extending diagonally of said unit and terminating in longitudinal alignment with an opposed side wall rearwardly of said king post.

13. In a combined bolster center filler and draft lug unit, the combination of, longitudinally directed side walls, a base plate joining said side walls, transversely spaced forward walls each extending transversely of said unit from a companion side wall toward an opposed side wall, cross-ribbing upstanding from said base plate, said cross-ribbing comprising a rib joined to each of said side walls and extending diagonally of said unit to terminate in longitudinal alignment with an opposed side wall, said ribs intersecting

intermediate said side walls, and a king post upstanding from said base plate and spaced longitudinally from the intersection of said ribs.

14. In a combined bolster center filler and draft lug unit, the combination of, longitudinally directed side walls, a base plate joining said side walls, transversely spaced forward walls each extending transversely of said unit from a companion side wall toward an opposed side wall, cross-ribbing upstanding from said base plate, said cross-ribbing comprising a rib joined to each of said side walls and extending diagonally of said unit to terminate in longitudinal alignment with an opposed side wall, said ribs intersecting intermediate said side walls, and a king post upstanding from said base plate between said ribs and spaced longitudinally from the intersection thereof.
